UNITED STATES PATENT OFFICE.

ALBERT RUDLER, OF OXFORD FURNACE, NEW JERSEY.

DYEING APPARATUS.

1,282,633.

Specification of Letters Patent. Patented Oct. 22, 1918.

Application filed April 13, 1918. Serial No. 228,425.

To all whom it may concern:

Be it known that I, ALBERT RUDLER, a citizen of France, residing at Oxford Furnace, in the county of Warren and State of New Jersey, have invented new and useful Improvements in Dyeing Apparatus, of which the following is a specification.

The invention relates to dyeing, and has for an object to provide an apparatus for dyeing various kinds and characters of silk, wool, cotton and mixed goods and material in pieces or skeins, or in any other manner.

Among other features the invention comprehends an apparatus for dyeing various kinds of materials, particularly materials which come in bulk or in rolls, as in the case of a bolt of cloth, and to this end use is made of a suitable vat and a frame, the latter being adapted to hold the cloth to be dyed in a manner which will insure effective action of the dye fluid contained in the vat, upon the material, and whereby further the particular construction and arrangement of the frame permits of effectively subjecting the cloth or material to the action of the fluid to obtain the best results. With this in mind, I aim to provide a dyeing apparatus that is so designed and constructed that a bolt of cloth or other material will be evenly subjected to the dyeing action of the fluid, so that the material will be uniformly dyed and the dyeing, when finished, will not result in a product that is dyed in blotches or spots only, but in which the product will be uniformly dyed throughout, the dyeing process and operation being further expedited by the particular arrangement and form of the device I employ.

In the further disclosure of the invention, reference is to be had to the accompanying drawing, constituting a part of this specification, in which similar characters of reference denote corresponding parts in all the views, and in which

Figure 1 is a fragmentary enlarged vertical sectional view of a part of the frame showing the arrangement of the holding needles.

Fig. 2 is a fragmentary horizontal sectional view taken through the structure shown in Fig. 1.

Fig. 3 is a vertical reduced sectional view taken through the vat and dye frame, showing the relative arrangement thereof, and

Fig. 4 is a horizontal sectional view taken through the structure shown in Fig. 3.

Referring more particularly to the views, the numeral 10 indicates a vat which may be of any preferable type and form of construction, but is here shown of angular configuration, the vat being of sufficient depth to prevent any splashing of the dye fluid when the frame, which is to be hereinafter described, is immersed therein. The frame is indicated by the numeral 11 and the same is of a substantially rectangular construction providing side pieces 12 and end pieces 13, with suitable connecting apparatus 14 preferably provided with a series of perforations 15. A plurality of studs 16 extend into opposed sides of the frame to swingingly support the frame upon a supporting frame or element 17, consisting of uprights 18 and a cross piece 19, the latter having connection with a depending cable 20 passing around a suitable pulley 21 carried on a shaft 22, the latter also carrying a tooth wheel 23 meshing with a beveled wheel 24 on a driving shaft 25. The cable 20 is wound on the pulley 21, and by operation of the driving shaft 70 it will be understood that the frame will be drawn upwardly to remove the same from the vat, or can be lowered to immerse the frame in the vat.

The frame 11 includes racks 26 adapted to hold the cloth or material, indicated by the numeral 27, and the rack consists essentially of a plurality of slide bars 28, there being preferably provided an upper pair and a lower pair of said bars, the ends of which are secured to the frame by bolts 29 passing through the apertures 15, so that the upper and lower pairs of bars can be brought together closely or spaced apart, depending upon the extent and amount of the cloth to be used and its width. Mounted to slide in the upper and lower bars of the rack and in the slots thereof, are holders 30 which holders may be better termed needle holders, in that they have secured therein projecting needles 31 extending horizontally to pass through the ends of the cloth and be seated in sliding cross pieces 32, adapted to slide in the slots of the bars 28, said cross pieces having longitudinal horizontal slots 33 therein 105 and the inner ends of which are enlarged as at 34.

Referring to the views it will be seen that any number of needles 31 may be carried on the needle holders 30, and that when the frame is removed from the vat the material is hung upon the needles so as to extend

vertically with respect to the frame, the needle holders then being advanced so that the ends of the needles will pass into the slots 33 of the cross pieces forming the seats 5 for the needles, thus securing the goods in position upon the frame, or more particularly upon the rack.

The entire frame is now lowered into the vat and subjected to the dye fluid contained 10 therein, and in order that the goods will be uniformly dyed, the frame, after the goods have been subjected to the action of the fluid, is raised from the vat and the entire frame swung upon the studs 16, so that that 15 portion of the goods which formerly was at the upper end of the frame, will now be at the lower end thereof, and the frame is now immersed in the vat so as to insure uniform dyeing of the goods.

20 It has been found by experience that in submerging goods in a vat of dye, the portion of the goods near the bottom of the vat was dyed a shade darker than the goods near the top of the vat, and it is in order 25 to overcome this deficiency that I have designed and constructed a frame so that it can be swung entirely around on the supporting frame of the apparatus. It will of course be understood that the needles can 30 be of any length and that any kind of goods can be supported upon the frame, depending of course upon the size thereof. Further it will be seen that the racks 26 can be adjusted on the uprights 14 so that the apparatus can accommodate goods of different 35 widths.

From the foregoing description, it will be seen that the device described is of simple construction; that by the raising and lowering 40 arrangement of the frame, the goods can be removed at any time from the vat and inspected, and then the frame turned around to bring the goods back into contact with the dye fluid, when the frame is immersed 45 in the vat, so that the goods which formerly hung near the top of the frame will now be near the bottom thereof, so as to positively receive the action of the dye fluid.

50 With a device of this character, the material can readily be placed in position on the frame for the dyeing process, and can be as easily removed, and by having the needles and needle holders arranged as described, the spacing of the different layers of goods will be effectively accomplished, particularly as shown in Figs. 3 and 4, it will be seen that in placing the goods upon the needles, the width of the goods will be 55 vertically disposed, and when a length of 60

the goods has been placed over the needles, the bolt of goods is brought back to place a second layer or length upon the needles, and so on until all of the bolt of goods has been supported upon the needles and 65 holders.

Although I have shown a particular form of my invention, I do not limit myself to the specific construction described herein; various slight changes may be made without departing from the spirit of the invention, and the scope of the latter is defined in the appended claims.

I claim:

1. A dyeing apparatus comprising in combination with a vat, a frame, means for lowering the frame into the vat or raising the frame out of the vat, horizontally disposed slotted racks adjustably carried on the frame, horizontally disposed needle holders slidably mounted on said racks, needles in said holders and means mounted to slide on the racks for seating the ends of said needles to support the goods to be dyed upon the needles between the needle 80 holders and said seating means.

2. In a dyeing apparatus, a supporting frame, a second frame mounted to swing upon the supporting frame, said second frame being revoluble upon the supporting frame, means for raising or lowering said supporting frame and said second frame without interfering with the revolving of said second frame upon the supporting frame, adjustable racks on said second frame, needle holders mounted to slide on said racks, needles on said needle holders to support the goods to be dyed, and means for seating the ends of said needles after the same have penetrated the goods to be 90 dyed.

3. In a dyeing apparatus, the combination with a vat and a vertically movable supporting frame, of a material-holding frame mounted to revolve upon said supporting frame and movable vertically with the latter into or out of said vat and needles on said material-holding frame for supporting the goods to be dyed thereon.

4. In a dyeing apparatus, the combination with a vat and a vertically movable supporting frame, of a material-holding frame mounted to revolve upon said supporting frame and movable vertically with the latter into or out of said vat, and adjustable means on said second frame for adjustably supporting the goods to be dyed.

In testimony whereof I affix my signature.

ALBERT RUDLER.
